FISHING TOOL

James F. Chappell, Mineola, Tex.

Application February 16, 1939, Serial No. 256,643

11 Claims. (Cl. 294—96)

This invention relates to new and useful improvements in fishing tools.

One object of the invention is to provide an improved fishing tool for inserting and removing drill bits, packers and other elements, from a well casing, tubing or the like.

Another object of the invention is to provide an improved fishing tool which is particularly adapted for use in oil field work and which includes retractable gripping elements arranged to be expanded into engagement with a tubular member so as to establish a positive connection between the tool and member, whereby said member is supported solely by the tool and may be run into or removed from the well bore with said tool.

An important object of the invention is to provide an improved tool, of the character described, which is adapted to be connected with a well device, whereby the device may be lowered into the well bore by means of said tool; said tool being constructed so that it may be readily disconnected from the well device at any desired time and removed from the bore to leave said device in the bore at the desired elevation, the removal of the tool clearing the well bore and obviating the possibility of said tool interfering with any of the well operations.

A further object of the invention is to provide an improved tool, of the character described, having radially movable gripping elements for engaging the device to be lowered or raised, which elements are constructed so that they remain in their retracted position during the lowering of the tool through a well bore, whereby the tool may be utilized to pick up a well device which has been previously set in the bore; said elements being arranged to be expanded into connecting position by an upward movement of the tool, thereby making it possible to readily make the connection with the device to be removed.

Still another object of the invention is to provide an improved tool adapted to be connected with a well device at the surface so that said device may be lowered through the well bore with said tool, said tool being constructed so that the gripping elements thereof may be readily retracted at any desired time and locked in such retracted position, whereby said tool may be disconnected from the well device and removed from the well bore.

A particular object of the invention is to provide an improved fishing tool, wherein a sleeve is associated with the latching means which holds the gripping elements in a retracted position, said

sleeve being arranged to be dropped from the surface so that said gripping elements may be positively locked in their retracted position when desired.

5 A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, showing a fishing tool constructed in accordance with the invention as it is being lowered into a member to be removed,

15 Figure 2 is a similar view showing the fishing tool connected to the member,

Figure 3 is a view similar to Figure 2 of the upper portion of the tool showing the movable elements locked in their upper position,

20 Figure 4 is horizontal, cross-sectional view taken on the line 4—4 of Figure 1,

Figure 5 is a horizontal, cross-sectional view 25 taken on the line 5—5 of Figure 3,

Figure 6 is a horizontal, cross-sectional view taken on the line 6—6 of Figure 1,

Figure 7 is a horizontal, cross-sectional view 30 taken on the line 7—7 of Figure 1,

Figure 8 is an enlarged isometric view, a portion of which is broken away, of the elongate sleeve having slots therein for receiving the arms,

Figure 9 is a similar view of the coupling collar,

35 Figure 10 is a similar view of the lower thimble,

Figure 11 is a similar view of the short collar, and

Figure 12 is a view, partly in section and partly 40 in elevation, of a modified form of the fishing tool connected to an ordinary pipe.

In the drawings, the numeral 10 designates a well casing of the usual construction through which a fishing tool A is arranged to be lowered on a wire line or cable 11. The fishing tool A includes a swivel socket 12 carried by the wire line 11 and having its bore screw-threaded to receive the upper end of an elongate, cylindrical mandrel 13. The swivel socket is rotatably mounted on the wire line and, therefore, the fishing tool is freely rotatable with relation to said wire line. The lower end of the mandrel is tapered or flared outwardly, whereby an external, frusto-conical or inclined expanding surface 14 is formed thereon. An enlarged, cylindrical head 55 15 is provided on the mandrel immediately below

the tapered surface 14, as is clearly shown in Figures 1 and 2, and is preferably made integral with said mandrel. The head is of greater diameter than the seat 14, whereby an external annular shoulder 16 is formed on the mandrel and surrounds the lower end of said seat. The lower end of the head 15 has its peripheral edge portion bevelled or tapered as shown at 15'.

A collar 17, having an internal diameter slightly greater than the external diameter of the mandrel 13, is slidably mounted on said mandrel above the tapered surface 14. A plurality of slots 18 are provided in the upper end of the collar 17, while a plurality of vertical grooves or recesses 19 are formed in the external surface of said collar as shown in Figure 11. The grooves 19 are inclined inwardly and downwardly from a point flush with the exterior of the sleeve to a point midway between the inner and outer surfaces thereof. Each slot 18 overlies one of the grooves 19 and has its bottom inclined or bevelled inwardly from the horizontal to form an inclined seat 18' for a short angular gripping element or dog 20.

The dogs 20 have their upper ends turned or bent upon themselves at an angle of less than 90 degrees, whereby the inclination of the upper ends of said dogs is complementary to the inclined seats 18' and grooves 19. The seats 18' serve to support the dogs which engage within the grooves 19 and have their inner surfaces contiguous to the inclined lower surface or bottom of said grooves as shown in Figure 1. Each dog is bent outwardly at 20' so that the lower portion of the dog extends substantially parallel to the mandrel 13 when said dog is within its groove and is supported by its seat. The lower extremity of each dog is bent upon itself at an angle greater than 90 degrees, or at right angles to the vertical upper portion of said dog, so as to form outwardly extending lugs 21, which are arranged to engage within the well device, or other member to be removed from the casing, as will be hereinafter explained.

A cylindrical thimble 22, having an internal diameter equal to the external diameter of the collar 17, is adapted to engage around the latter, as shown in Figures 1, 2 and 7. A plurality of vertical grooves or recesses 23 are formed in the inner surface of the thimble 22 at its lower portion, as is clearly shown in Figure 10. Each recess is arranged to receive one of the dogs 20 as shown in Figure 6, whereby said dogs will be confined between the collar 17 and thimble 22. A pair of diametrically opposed openings 17' are provided in the collar 17, while a similar pair of openings 22' are formed in the thimble 22, whereby said collar and thimble may be fastened together by a pair of screws 24 so as to hold the dogs 20 in place. The upper end of the thimble 22 is internally screw-threaded, as shown at 25, and an elongate cylindrical tube 26 is threaded thereinto. The tube 26 has substantially the same diameter as the collar 17 and is slidable with relation to the mandrel.

A coupling collar 27, having a screw-threaded bore, is secured to the upper end of the tube 26 and is provided with an internal, annular shoulder 28 at its upper end (Figure 9). An elongate, cylindrical sleeve 29 is screw-threaded into the upper end of the coupling 27 and has its lower end abutting the upper end of the tube 26. The sleeve has the same internal diameter as the tube so as to be slidable on the mandrel and is formed with a plurality of longitudinal, elongated slots

30 between its externally screw-threaded ends, as is clearly shown in Figure 8. The slots 30 have their upper ends 30' rounded or fluted upwardly and outwardly, while their lower ends are provided with internal, vertical flanges 31 which form external, horizontal shoulders 32. The internal shoulder 28 of the coupling 27 is in the same horizontal plane as the shoulders 32, as shown in Figures 1, 2 and 3, whereby recesses for receiving the reduced lower ends of a plurality of upright arms 33 are provided.

The arms 33 have their upper ends rounded or bevelled, as shown at 33', so as to be complementary to the fluted upper ends 30' of the slots 30, as is clearly shown in Figure 1. The bevelled ends 33' of the arms are held in engagement with the fluted ends 30' of the slots by a cylindrical thimble 35 which is screw-threaded upon the upper end of the sleeve 29. The upper end of the bore of the thimble 35 is reduced so as to snugly engage and be slidable on the mandrel, while the extreme lower end of said bore is tapered or flared outwardly at 35' to engage around and abut the outer surface of the upper ends of the arms. Thus, the arms 33 are held in position on the sleeve 29 by the coupling 27 and thimble 35. A lug or projection 34, having downwardly and inwardly inclined upper and lower surfaces, is provided on the inner surface of each arm 33 adjacent its reduced lower end, and each lug is arranged to engage within an external groove or recess 13' formed in the mandrel 13, as will be hereinafter fully explained.

The well device, tool or other member B to be inserted within or removed from the well casing 10, or from the well bore if no casing is located therein, is provided with an axial, cylindrical bore or recess 36 in its upper end. An annular, bevelled seat 37' is formed within the bore 36 by an internal, annular groove 37 provided therein. The upper surface of the annular groove is inclined upwardly and outwardly to form an annular downwardly extending shoulder or lips 38 which is arranged to be engaged by the lugs 21 of the dogs 20 to connect the member B to the fishing tool A. An internal, annular, bevelled seat 36' surrounds the upper end of the bore 36 of the member, which seat is adapted to co-act with the seat 15' of the head 15 for guiding said head into said bore.

In operation, the fishing tool A, having its tubular elements in the position shown in Figure 1, is lowered into the well casing 10 on the wire line 11. It is noted that the elements carried by the mandrel 13 will tend to ride upwardly thereon so that the thimble 35 abuts the socket 12, due to the fact that said mandrel is connected directly to said socket and that the members are slidable thereon. The dogs 20 will, of course, be in their normal or inward position, as shown in Figure 1. The lowering of the fishing tool is continued until the head 15 of the mandrel enters the bore 36 of the member B. If the head is not in alignment with the bore, the bevelled seats 15' and 36' of said head and bore, respectively, will coact to guide the former into the latter. In the event that the dogs are engaging the shoulder 16 when the head 15 enters the bore it will be seen that said dogs will strike the bevelled shoulder 36', whereby further downward movement thereof will be arrested until the mandrel has lowered sufficiently to move its cylindrical portion opposite said dogs, at which time the dogs may swing inwardly to retract the same and permit them to enter the bore of the member B.

Downward movement of the fishing tool A is halted when the lugs 21 of the dogs 20 are below the groove 37 or in substantial horizontal alignment with the bevelled seat 37'. At such time, the dogs will move downwardly and abut the frusto-conical seat 14 of the mandrel, whereby the lugs 21 of said dogs will be forced outwardly a slight distance into the annular groove 37. The fishing tool and wire line are then raised which will move the mandrel upwardly with relation to the tubular elements mounted thereon. These elements will remain stationary, since the lugs of the dogs will engage the inclined shoulder 38 of the member B. The upward movement of the mandrel causes the dogs to move outwardly and downwardly along the seat 14 until they strike and rest upon the shoulder 16 of said mandrel as shown in Figure 2. At this time, the collar 17 will engage the upper edge of the seat 14 and the thimble 22 will be contiguous to the outer surface 20 of the dogs to hold the same in position. The member B is thus coupled to the fishing tool A and upon removing the latter from the casing, the former is also removed therefrom.

It will thus be seen that an effective and quick coupling of the fishing tool with the member B may be made within the casing. It is pointed out that the member B may be inserted within the casing by the fishing tool as well as removed therefrom. It is also noted that due to the bevelled seats 15' and 36', the head 15 is positively guided into the bore of the member.

When it becomes desirable to remove the fishing tool A from the well casing and leave the member B therein, it is necessary to disconnect the same. To effect this disconnection, the mandrel 13 is moved downwardly from the position shown in Figure 2, whereby the head 15 of said mandrel is lowered within the bore 36 of the member B. This permits the dogs 20 to move downwardly until the lugs 21 on said dogs strike the bevelled seat 37', at which time further downward movement of the dogs 20, sleeve 22, and its associate parts, is arrested. Lowering of the mandrel is continued until the lower end of the socket 12 strikes the upper end of the thimble 35 (Figure 3) and when this occurs, the annular groove 13' of the mandrel is aligned with, or in the same horizontal plane as, the lugs 34 of the arms 33. The lowering of the mandrel, as above set forth, also moves the tapered portion 14 into a plane below the dogs 20 which have their lugs 21 within the annular groove 37 of the member B. After the parts have moved to this position, with the lugs 34 aligned with the groove 13' in the mandrel and the tapered portion 14 misaligned with the dogs 20, a heavy sleeve or pipe section 39 is dropped or lowered into the well casing, it being preferable to drop said sleeve on the wire line, whereby said line guides the same into position. The pipe section 39 is of such diameter that it will engage around and slide over the socket 12 and thimble 35, and said pipe has its lower end internally bevelled so that it will be guided into alignment with said socket and thimble. The bevelled lower end of the pipe section will ride over the arms 33 and come to rest upon the upper end of the coupling 21. This will cause the arms to be forced inwardly so as to move the lugs 34 thereof into the groove 13' of the mandrel, as is clearly shown in Figure 3. Such engagement of the lugs within the groove locks the tubular elements in the position shown in Figure 1 with relation to each other.

Continued downward movement of the fishing

tool will cause the lugs 21 of the dogs to disengage the shoulder 38 and engage the bevelled seat 37' of the member B, which engagement will force the dogs inwardly to their original position. This inward movement of the dogs is permitted because the seat 14 and head 15 of the mandrel have moved away from said dogs and are no longer holding the same in their outer or expanded position. With the dogs in their inward or unexpanded position, the wire line 11, pipe section 39 and fishing tool A may be lifted through the casing 10 and the member B will remain within said casing.

Obviously, the dropping or lowering of the pipe section 39 causes the same to strike the upper end of the coupling 21, whereby said coupling and the other elements slidably mounted on the mandrel will be jarred. This jarring action of the pipe section will tend to dislodge the lugs 21 of the dogs from their engagement with the shoulder 38 so as to aid the inward movement of said dogs.

It is pointed out that the fishing tool A may be employed for inserting a tool or other member B within a casing as well as for removing a member therefrom. Also, the diameter of the fishing tool may be reduced so that it may be operated within a tubing of small diameter. In either case, the operation of the fishing tool would be accomplished in the same manner, as hereinbefore set forth, and the connection and disconnection of the fishing tool to the member may be quickly and easily made.

In Figure 12, another form of the invention 35 is shown and includes a cylindrical mandrel 13a having an elongated bevelled seat 14a and head 15a. The short collar 17, thimble 22, tube 26 and the other elements are slidably mounted on the mandrel in the same manner as in the other form. A plurality of angular dogs 40, similar to the dogs 20 and having outwardly extending toothed slips 41 on their lower ends, are supported by the inclined seats 18' of the collar 17.

This form of the invention may be employed 45 to insert or remove a section of pipe, tubing or other member C having a smooth bore 42, into or from a well casing. When it is desired to connect the fishing tool to the member C, it is lowered into the casing on a wire line (not shown) in the same manner as the other form hereinbefore described. The elements carried by the mandrel will be in the position shown in Figure 1 and the dogs 40 will be in their normal or retracted position. As soon as the dogs are 50 within the member C, downward movement of the tool is suddenly stopped which will cause the elements carried by the mandrel to move downwardly thereon. The weight of these elements will be exerted upon the collar 17 and dogs 40 and will force the latter downwardly and outwardly along the seat 14a, whereby the slips 41 of said dogs will move outwardly into engagement with the bore 42 of the member C.

The mandrel is then pulled upwardly so that 65 the shoulder 16' of the head 15a will be in close proximity to the underside of the dogs, whereby the toothed slips will firmly grip the bore of the member C. This movement of the mandrel 13a relative to the dogs 40 is made possible by reason 70 of the fact that the toothed slips of said dogs have a tendency to stick to the bore of the member. Further expansion of the dogs is permitted by the length of the bevelled seat 14a so that, in the event the bore of the member has become 75 enlarged, a positive gripping of the slips is as-

sured. Of course, this form of the invention may be disconnected from the member C in a similar manner to that employed in disconnecting the first form, as has been hereinbefore explained (Figure 3). To bring about this disconnection the mandrel 13a is moved downwardly from the position shown in Figure 12, whereby the head 15a of said mandrel is lowered through the bore 42 of the member C. Since the toothed slips 41 of the dogs are in gripping engagement with the bore of the member, said dogs will remain in their expanded position during the downward movement of the mandrel. Lowering of the mandrel is continued until the lower end of the socket 12 contacts the upper end of the thimble 35, at which time, the bevelled seat 14a will be in a plane below the dogs 40. This movement of the mandrel also aligns the lugs 34 of the arms 33 with the annular groove (not shown) of said mandrel. When the parts are in this position, the pipe section 39 is dropped into the well casting on a wire line to move the lugs 34 of the arms 33 into the annular groove of the mandrel, whereby said parts will be locked in such position. It is noted that the jarring action of the pipe section 39 is especially important in this form, since it will tend to dislodge the toothed slips 41 of the dogs 40 from their gripping engagement with the bore of the member C, whereby they will move to their inward position.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. A fishing tool including, a support, gripping means slideable on the support and co-acting therewith so as to be expandable and retractable radially thereof, latching means on the support and associated with the gripping means for latching said gripping means in a retracted position, and means arranged to be lowered from the surface and adapted to be engaged over the latching means externally of the support for positively holding the same in its latched position.

2. A fishing tool including, a support, gripping means slideable on the support, said support having a tapered portion for co-acting with the gripping means to expand and retract the arms, latching means on the support and associated with the gripping means for latching said gripping means in a retracted position, and means arranged to be lowered from the surface and adapted to be engaged over the latching means externally of the support for positively holding the same in its latched position.

3. A fishing tool including, a support, gripping means slideable on the support and co-acting therewith so as to be expandable and retractable radially thereof, and latch arms slideable on the exterior of said support and associated with the gripping means, the latch arms being arranged to engage the exterior of said support to latch said means in a retracted position.

4. A fishing tool including, a support, gripping means slideable on the support and co-acting therewith so as to be expandable and retractable radially thereof, latch arms slideable on said support and associated with the gripping means, the latch arms being arranged to engage said support to latch said means in a retracted position, and means arranged to be lowered from the sur-

face and adapted to be engaged over said latch arms externally of the support for positively holding the same in engagement with the support.

5. A fishing tool including, a support, gripping means slideable on the support, tapered means on the support co-acting with the gripping means, whereby said gripping means is expandable and retractable radially of the support, latch arms slideable on said support and associated with the gripping means, the latch arms being arranged to engage said support to latch said means in a retracted position, and a sleeve adapted to be engaged over said latch arms for positively holding the same in engagement with the support.

15 6. A fishing tool including, a support having a tapered portion near its lower end, a carrier slidably mounted on the support, gripping means on said carrier arranged to co-act with the tapered portion of the support so as to be expandable and retractable radially of said support, the support having a recess in its external surface, and a pivoted latch on the carrier adapted to engage the recess when moved inwardly of the support, and a sleeve arranged to engage over the carrier and the latch to move said latch inwardly to its locking position to lock the carrier and support together in a position holding the gripping means in a retracted position.

7. A fishing tool including, a mandrel having 30 a portion of its external surface inclined outwardly, an elongate carrier slidably mounted on the mandrel, gripping elements pivotally mounted on the carrier and arranged to co-act with the inclined portion of the mandrel, whereby said 35 elements are expandable and retractable radially of the mandrel, and a pivoted latch carried by the upper end of the carrier and arranged to engage the exterior of the mandrel to lock the mandrel and carrier to each other in a position holding the inclined portion of the mandrel out of alignment with the gripping elements.

8. A fishing tool including, a mandrel having 45 a portion of its external surface inclined outwardly, an elongate carrier slidably mounted on the mandrel, gripping elements pivotally mounted on the carrier and arranged to co-act with the inclined portion of the mandrel, whereby said 50 elements are expandable and retractable radially of the mandrel, the mandrel having an annular groove in its peripheral surface, and latching members mounted in the carrier and movable radially of the mandrel, said members being adapted to engage within the groove to lock the mandrel and carrier together, the groove and members being so disposed with relation to each other that they are aligned for engagement when the tapered portion of the mandrel is misaligned with the gripping elements.

9. A fishing tool including, a mandrel having 60 a portion of its external surface inclined outwardly, an elongate carrier slidably mounted on the mandrel, gripping elements pivotally mounted on the carrier and arranged to co-act with the inclined portion of the mandrel, whereby said 65 elements are expandable and retractable radially of the mandrel, the mandrel having an annular groove in its peripheral surface, latching members mounted in the carrier and movable radially of the mandrel, said members being adapted to engage within the groove to lock the mandrel and carrier together, the groove and members being so disposed with relation to each other that they are aligned for engagement when the tapered portion of the mandrel is misaligned with the gripping elements, and a sleeve engageable

over the carrier and the locking members to move said members to an inner position in engagement with the groove and to hold said elements in such position.

10. A fishing tool including, a mandrel having a portion of its external surface inclined outwardly, an elongate carrier slidably mounted on the mandrel, gripping elements pivotally mounted on the carrier and arranged to co-act with the inclined portion of the mandrel, whereby said elements are expandable and retractable radially of the mandrel, the mandrel having an annular groove in its peripheral surface, a latching assembly mounted on the carrier comprising an elongate collar surrounding the mandrel and having a plurality of vertical slots therein, and a radially movable latch member in each slot adapted to engage the annular groove in the mandrel to lock the mandrel and carrier to each other, the disposition of the latch members and groove be- 20

ing such that these parts are aligned with each other when the inclined portion of the mandrel is misaligned with the gripping elements and said elements are retracted.

11. A fishing tool including, a mandrel having a portion of its external surface inclined outwardly, an elongate carrier slidably mounted on the mandrel, gripping elements pivotally mounted on the carrier and arranged to co-act with the inclined portion of the mandrel, whereby said elements are expandable and retractable radially of the mandrel, each gripping element comprising a gripping slip having teeth on its outer surface, and a pivoted latch carried by the upper end of the carrier and arranged to engage the exterior of the mandrel to lock the mandrel and carrier to each other in a position holding the inclined portion of the mandrel out of alignment with the gripping elements.

JAMES F. CHAPPELL.
